(57) **CLAIM**

The ornamental design for the combined nipple and ring, as shown and described.

DESCRIPTION

FIG. 1 is a perspective view of the combined nipple and ring, showing my design;

FIG. 2 is a front elevational view of the combined nipple and ring of FIG. 1, the rear elevational view being identical;

FIG. 3 is a side elevational view of the combined nipple and ring of FIG. 1, the opposite side elevational view being identical;

FIG. 4 is a top view of the combined nipple and ring of FIG. 1; and,

FIG. 5 is a bottom view of the combined nipple and ring of FIG. 1.

The broken lines showing the letters in FIGS. 1, 2 and 3 are for illustrative purposes only and form no part of the claimed design.

1 Claim, 2 Drawing Sheets***FIG. 1***

FIG. 2
